Primary Examiner — Lilyana Bekic*Assistant Examiner* — Samantha K Pollack(74) *Attorney, Agent, or Firm* — Crowell & Moring LLP(57) **CLAIM**

The ornamental design for a biological sample analyzer as shown and described.

DESCRIPTION

FIG. 1 is a front perspective view of a biological sample analyzer showing our new design;

FIG. 2 is a rear perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom view thereof.

1 Claim, 5 Drawing Sheets(56)
